PIPE CLEANERS

Bernard E. Thaxton, Washington, D. C.

Application May 15, 1953, Serial No. 355,251

3 Claims. (Cl. 131—243)

The present invention relates to improvements in smoking-pipe cleaners and more particularly relates to an improved pipe cleaner utilizing air pressure as the cleaning agent.

I am aware that heretofore air pressure has been utilized to clean smoking pipes. However, in the prior types of pipe cleaners, the air is continuously supplied and so is only effective to a limited extent. Furthermore, if caking is present in the bottom of a pipe bowl, prior air-pressure types of pipe cleaners were inadequate. The pipe cleaners heretofore proposed also have been difficult to handle when used in cleaning smoking pipes and performing like operations.

It is therefore a primary object to provide an improved smoking pipe air pressure cleaning device which will overcome difficulties existent with prior types of smoking pipe cleaners.

Another object of the present invention is to provide an improved device for cleaning smoking pipes wherein air pressure is the cleaning agent and wherein the arrangement is such that the device can be held in one hand while the pipe to be cleaned is held in the other, and yet whereby the delivery of air pressure is discontinuous and more in the nature of periodic spurts so as to more effectively clean the passageways of smoking pipes.

A further object of the present invention is to provide an improved smoking pipe passageway cleaning device which is rigid in construction, yet lightweight and easily manipulated in one of an operator's hands.

Still another object of the present invention is to provide an improved smoking pipe cleaning device construction which fits comfortably in an operator's hand and which is shaped so that the air delivery conduit may easily be urged against a tire valve type of arrangement at the inlet end of the cleaning device at intervals by the same hand of the operator so that the air pressure can be delivered in periodic spurts with ease and by the use of but one hand of the operator, the other hand being free to hold the pipe.

The best embodiment of my invention generally is comprised of an elongated nozzle piece which may be constructed from a suitable piece of tubing, the outlet end being provided with a nozzle opening which is preferably of reduced diameter relative to the bore in the tubing. The outlet end is rounded off and is shaped so as to be received in the mouthpiece receiving recess of the pipe stem. The inlet end of the nozzle piece has a tire valve type assembly therein with which a conventional air chuck is cooperatively associated, and to which chuck an air hose or conduit of compressible material is connected. Intermediately of the ends of the nozzle piece and closely adjacent the hose coupling end thereof is an elongated cross bar of substantially arcuate cross section throughout its length. The crossbar is rigidly secured to the nozzle piece and a pair of rigidifying webs join the nozzle piece to the cross bar in a plane substantially perpendicular to the axis of the cross-bar. The

2

cross-bar inside surface has spring fingers longitudinally spaced carried thereby so that a cleaning stick can be releasably carried thereby. The cleaning stick is wire-like with one end bent to provide a gripping portion while the other end is adapted to be inserted through the passageway of a pipe stem to break through any caking existent at the opening to the passageway in the bottom of the pipe bowl.

In the drawings:

Fig. 1 is an exploded perspective view showing the cleaning device of the present invention;

Fig. 2 is an inlet end elevational view of the device;

Fig. 3 is a side elevational view, partially in section, showing the manner in which the device of the present invention is employed for cleaning a pipe; and

Fig. 4 is a bottom plan view partly in section showing the relationship between the air chuck of the inlet conduit and the inlet end of the nozzle piece for delivering spurts of air pressure to the outlet nozzle.

Referring more particularly to the drawings wherein like numerals designate like parts throughout, it will be seen that the smoking pipe cleaning device of the present invention is designated generally by the numeral 10 and is comprised of a nozzle piece 12, cross-bar handle element 14, a conventional air chuck and air pressure conduit 16 and cleaning stick 18.

The nozzle piece 12 is comprised of an elongated rigid integral tubing portion, the outlet end of which is rounded at 20 and provided with a reduced diameter opening at 22. The opposing or inlet end of the nozzle piece which is shown as internally threaded at 24 has threaded therein a substantially conventional tire valve assembly 23. An example of the tire valve assembly that can be used is shown in Patent No. 1,991,974, issued to L. C. Broecker, issued February 19, 1935.

The specific tire valve assembly 23 is used solely for the purpose that it provides a convenient means for unseating the pin, hereinafter described, of the air chuck or coupling pin, also hereinafter described. Actually, any rigid pin-like member disposed substantially concentrically of the inlet end of the nozzle piece would serve the same function as the tire valve specifically shown, but since it is relatively easy to provide for insertion of the tire valve assembly within the inlet end of the nozzle piece, it is perhaps preferable that this construction be used.

The cross-bar handle element 14 which is elongated and rigid is provided with a centrally located aperture at 26 of a size to receive the nozzle piece 12 therethrough and the element 14 is rigidly secured in perpendicular relation to the nozzle piece adjacent the inlet end 24 forming a T-shaped smoking pipe cleaner, solder or other suitable means being employed for forming the joint as at 28.

A pair of substantially triangularly shaped rigidifying webs 30 and 32 are soldered or otherwise secured in substantially coplanar relationship on opposing sides of the nozzle piece 12 at 34 and 36 and to adjacent surface portions of the cross-bar handle element at 38 and 40, the axis of the latter element being substantially perpendicular to the plane of the webs 30 and 32.

The cross-bar handle element has an arcuate cross-section as viewed transversely of its axis and this in part is to provide a convex surface 42 adapted to comfortably fit against the fingers of the hand of the operator of the device. The concave surface 44 has a pair of spring fingers 46 and 48 longitudinally spaced and secured thereto so as to releasably hold the cleaning stick 18, to be described hereinafter, within the confines of the cross-bar handle element.

The air chuck and delivery conduit 16 is conventional and includes a coupling head at 50 adapted to be en-

gaged over the inlet end at 24 of the nozzle piece. The head 50 conventionally includes an outlet check valve which is opened when urged against means such as the conventional tire valve. The hose or conduit is made of flexible, rubber-like material so as to be easily manually compressed and bent.

The cleaning stick 18 is formed of wire-like material and is relatively stiff and has a sufficiently small diameter as to be received in the passageway 52 of the pipe stem 54 through the mouth piece receiving socket at 56 to which the usual mouth piece is removably attached. The stick 18 has one end thereof arcuated so as to provide a handhold at 60, the width of which is less than the inside width of the cross-bar handle element so as to be received therein. The shank portion of the stick 18 is easily removably engaged beneath the spring fingers 46 and 48, as will be understood.

In operation, when it is desired to clean the pipe 11, and if any caking exists in the bottom 62 of the bowl of the pipe which would prevent passage of the air through the passageway 52 of the stem, the stick 18 is employed by insertion from the mouth piece socket end of the stem so as to break up any caking at 64. Next, the stick is removed from the stem and replaced beneath the spring fingers 46 and 48. Finally, the device is gripped in the operator's hand as shown in Fig. 3 with the conduit 16 extending from the palm of the operator's hand past the upper arcuate edge 66 of the handle element 14, and with the air chuck 50 engaged over the inlet end of the nozzle piece, the conduit being connected with a suitable source of air pressure. The outlet end 20 of the nozzle piece is engaged in the socket 56 of the pipe stem. The air chuck 50 is pressed against the inlet end of the nozzle piece so as to inter-engage the pins 57 and 59 of the tire valve and air chuck, respectively (see Fig. 4) so as to unseat the tire valve and air chuck valve and pass air through the passageway 52.

In order to more effectively employ the air pressure as a cleaning medium, the operator periodically releases the pressure of his palm against the chuck so as to permit the tire valve and air chuck valve to close thereby temporarily shutting off passage of air pressure. Upon renewing pressure and opening the valves, a shot of air passes into the pipe stem, the shock of the shot of air acting to effectively perform the cleaning. The pressing and releasing operation is repeated until cleaning is completed.

The cleaning device of the present invention may be utilized by the individual who would utilize the air hoses provided for filling tires at gasoline stations but is particularly designed for use in tobacconist shops where a separate air supply may be provided and the assembly used as a convenience to the customer.

While the device has been described for use in cleaning smoking pipes, it is to be realized that other uses will readily suggest themselves.

The pipe cleaner may be made of any suitable material such as from plastic, metal, or combinations of plastic and metal.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equiva-

lents, are therefore intended to be embraced by those claims.

I claim:

1. A smoking pipe cleaner comprising an elongated rigid integral air nozzle adapted to be engaged at one end in the mouth piece receiving recess of a pipe stem, an elongated rigid integral cross-bar permanently mounted on said nozzle adjacent the other end thereof and perpendicular thereto, said other end extending from said cross-bar and providing a nipple adapted for coupling with a source of air pressure, and a compressible conduit adapted to be coupled with said nipple, said cross-bar having an arcuate cross section transversely of its length for comfortably receiving the operator's fingers thereabout and to also receive a portion of said conduit thereagainst so that the operator may selectively compress the conduit against the cross-bar and interruptedly release air pressure through the conduit to the nozzle for cleaning the pipe.

2. A smoking pipe cleaner comprising an elongated rigid integral air nozzle adapted to be at one end engaged in the mouth piece receiving recess of a pipe stem, an elongated rigid integral cross-bar permanently mounted on said nozzle adjacent the other end thereof and perpendicular thereto, said other end extending from said cross-bar and providing a nipple adapted for coupling with a source of air pressure, a compressible conduit adapted to be coupled with said nipple, said cross-bar having an arcuate cross section transversely of its length for comfortably receiving the operator's fingers thereabout and to also receive a portion of said conduit thereagainst so that the operator may selectively compress the conduit against the cross-bar and interruptedly release air pressure through the conduit to the nozzle for cleaning the pipe, and a cleaning stick adapted to be used for initially breaking through any caking existent at the opening to the passageway in the bottom of the bowl of the pipe, said cross-bar having spaced spring fingers on its inside surface for releasably holding said cleaning stick.

3. A smoking pipe cleaner comprising an elongate air nozzle adapted to be engaged at one end in the mouth piece receiving recess of a pipe stem, and an elongate cross-bar secured to said air nozzle adjacent the other end thereof, said other end of the air nozzle extending from said cross-bar and providing a nipple adapted for coupling with a compressible conduit leading to a source of air pressure, and said cross-bar having an end portion thereof provided with a concave surface opening toward said nipple to receive a portion of the conduit thereagainst so that the operator may selectively compress the conduit against the cross-bar and interruptedly release air pressure through the conduit to the nozzle for cleaning the pipe.
